UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

DESIGN FOR A PISTOL.

50,354.

Specification for Design.

Patented Feb. 20, 1917.

Application filed September 30, 1915. Serial No. 53,468. Term of patent 14 years.

To all whom it may concern:

Be it known that I, CHARLES F. LEFEVER, a citizen of the United States of America, residing at Plymouth, in the county of Wayne and State of Michigan, have invented a certain new, original, and ornamental Design for a Pistol, of which the following is a specification, reference being had therein to the accompanying drawings, forming part thereof, in which—

I claim:

The ornamental design for a pistol, substantially as shown.

CHARLES F. LEFEVER.

Witnesses:

E. C. HOUGH,
W. B. LOMBARD.
